FLOYD C. FURLOW, OF MONTCLAIR, NEW JERSEY, ASSIGNOR TO OTIS ELEVATOR COMPANY, OF JERSEY CITY, NEW JERSEY, A CORPORATION OF NEW JERSEY.

ELEVATOR-DOOR MECHANISM.

1,228,201.

Specification of Letters Patent.

Patented May 29, 1917.

Application filed August 20, 1915. Serial No. 46,419.

To all whom it may concern:

Be it known that I, FLOYD C. FURLOW, a citizen of the United States, residing in Montclair, in the county of Essex and State 5 of New Jersey have invented a new and useful Improvement in Elevator-Door Mechanisms, of which the following is a specification.

My invention relates to elevator apparatus, and more particularly to an improved 10 mode of operation and system of control for elevator hatchway gates, the invention being more particularly adapted for use in conjunction with freight elevators.

In certain elevator installations involving 15 the transportation of power or hand operated vehicles such as baggage trucks, automobiles, street cars, etc., it is found desirable to do away with the services of a permanent 20 elevator operative; the idea being that the operative of the power vehicle shall operate the elevator car also. In the furtherance of this idea, it is desirable to provide means which shall require no manual effort on the 25 part of the operative, for controlling the operation of the hatchway gates. To this end it is one of the objects of the present invention to provide improved means for operating the hatchway gates, together with a novel 30 system of control, the said system being controllable by the power vehicle itself upon approaching the elevator car or upon leaving the latter, one of the most essential features residing in the automatic closing of 35 the hatchway gate after the exit of the vehicle from the elevator car, this arrangement eliminating the objectionable feature of an operative having to stop his vehicle to go back and close the gate.

Other novel features of the invention will 40 be set forth fully hereinafter, the novel combinations and arrangement of parts being set forth in the appended claims.

In the accompanying drawings, Figure 1 45 illustrates more or less diagrammatically a push button elevator system together with my improved means for operating the hatchway gates and a controlling system therefor, the various parts assuming such relative 50 positions as obtained with the hatchway gates closed; Fig. 2 is a view somewhat similar to Fig. 1 but with the parts assuming

such relative position as attend the open hatchway gates, a modified system of control for the hatchway gates being also illustrated 5 in this view.

With reference more particularly to Fig. 1, the elements will first be designated, and the operation thereof described thereafter.

The elevator car C, may be driven in any 60 well known manner, and by any well known means, such for example as by the motor M, the latter being provided with a shunt field winding S. Electro-magnetic reversing switches R, R' control the direction of rotation of the motor, and an accelerating magnet A controls the motor starting resistance X. A floor controller B, floor magnets C, non-interference magnet D, door contacts d, 65 hall push buttons b and car push buttons c, 70 operate in a well known manner to control the operation of the elevator car C. The parts thus far described are well known in the art, the push button system of control being substantially the same as shown 75 in the Ihlder Patent, No. 683,689, granted October 1, 1901, thus such elements have been described only in general, since they form no particular part of the present invention.

Coming now to the elements which more essentially constitute the subject matter of the present invention, such will be described more in detail. Elevator floor or hatchway landings are designated 1 and 2, these landings being of a special construction, and each being provided with a set of vertically movable gates G, the gates on one side of the hatchway being termed "entrance" and the gate on the opposite side "exit". The 80 provision of the two gates at each landing, eliminates any possible interference between vehicles passing "on" and "off" the elevator at the same time, it being proposed that the gates on one side of the hatchway shall be 85 used as the approach or entrance, and the gates on the opposite side of the hatchway as exit, this system being also convenient for the vehicle drivers since it eliminates backing of the vehicle off of the elevator 90 platform.

At each exit landing there is provided two yieldable floor sections H, these sections being spaced apart a distance corresponding

2

to the wheel base of a vehicle. In the present instance each of these floor sections is shown hinged at one end, the sections when in normal position as shown, being flush 5 with the adjoining floor, and the free ends of each section being supported by any suitable form of yielding element such as a coil spring 3. Associated with each floor section are electrical contacts 4, these contacts being 10 normally open as shown, and adapted to be closed by the actuation of the floor section.

At each entrance landing there is provided a single yieldable floor section H', which sections are made somewhat greater 15 in length than the sections H. The sections H' are hinged at one end, their free ends being supported by any suitable yielding element such as a coil spring 3'. Associated with each section H' is an electrical switch 20 device 5, whose contacts are normally closed as shown, and adapted to be opened by the actuation of the floor section.

Coming now particularly to my improved gate operating mechanism, it comprises a 25 cam member such as J, carried by the elevator car, the cam being pivotally connected at one of its ends 6 to the elevator car. The cam as shown in Fig. 1 is in its inoperative or retracted position. The cam is actuated 30 to an operative position, as shown in Fig. 2, by means of a small electric motor K, which actuates a winding drum 7, the drum being connected to the free end of the cam by a rope or cable connection 8.

35 There is positioned in the elevator hatchway at each landing, a pair of rails 9, upon which, rides a traveler 10. A pair of ropes or cables 11, are connected at one of their ends to the elevator gates G, these cables 40 being guided by idlers 12 and 13, to a pulley 14 which is movable with the traveler 10, the other ends of the cables being fixed at 15. With this arrangement it will be seen that the opening or closing of both gates at 45 a landing will be effected simultaneously, the gates being shown in closed position in Fig. 1, and in open position in Fig. 2, the opening thereof being effected by actuation of the traveler 10, toward the right hand. 50 The traveler is adapted to be actuated by means of the cam J on the car, the cam co-acting with a roller 16 on the traveler. The gates are maintained in their raised position by means of the cam J, there being 55 provided on the elevator car, an electrically controlled dog, 17, which is adapted to engage a slotted portion 18 of the cam J, upon the latter attaining its full actuated position.

60 In this manner, the gates are maintained in opened position as illustrated in Fig. 2. The dog 17 in its operation to engage the cam J is self-acting, the same being actuated by means of a spring 18 interposed between 65 a fixed member 19 and a collar 20

carried by the dog. The dog is disengaged from the cam by means of an electromagnet L, and the cam when released is returned to its inoperative position by means of a spring 21. In this manner the gates are permitted 70 to drop by their own weight to closed position.

At each landing there is provided, what I will herein term a non-interference or protective contact device, designated P, this device being controlled by the traveler 10. The device comprises simply a fixed contact 31 which is adapted to be engaged by a contact 32, movable with the traveler. As will be noted these contacts are opened with 80 the gates in closed position, as illustrated in Fig. 1, and with the gates in raised or open position, the contacts are closed as illustrated in Fig. 2.

Contacts 4, 4, contact device P, and switch 5, act conjointly to control a circuit for the electromagnet L, a parallel circuit for the said magnet being controlled by means of contacts 22, associated with each of the car push buttons e. The contacts 23, associated 90 with said buttons, control the car operating circuit, and it is to be particularly pointed out here, that the car push buttons are constructed in a manner such that only a single push thereon is necessary to close the contacts 22 and 23, controlling the circuits for the magnet L and car operation respectively.

At each entrance landing there is provided a push button e by means of which the motor K is indirectly controlled, this 100 push button directly controlling a winding 24 of a relay magnet O whose contacts 25 together with a switch device 26 controlled by the cam J control a self-holding circuit for the winding 24, which circuit includes 105 the motor K. The switch device 26 comprises a contact 27 which is movable by the cam J, over a fixed contact segment 28, the arrangement being such, that the contact 27 rides off the segment 28, when the cam attains a full actuated position and engaged by the dog 17. The provision of the relay magnet O makes it unnecessary for one to keep the push button pressed, while the motor K is performing its function of actuating the cam to its full operative position, since the relay and the switch device act conjointly, directly to control the motor K, after a push button e is once operated. Contacts 29 are positioned at each floor landing, 110 a circuit therebetween being completed by means of a contact shoe 30, carried by the elevator car, this shoe with the car at the landing being adapted to span the said contacts. These contacts are included in independent circuits with the push buttons e at their associated floors. Similar contacts 29' are positioned in the elevator hatchway at 115 a point substantially midway between the travelers 10, these contacts likewise being 120 130

adapted to be engaged by the contact shoe 30 as the elevator car is ascending or descending, and having the same function as the push buttons *e*, that is, they indirectly control a circuit for the motor *K*.

The operation of the various elements and the system of electrical circuits will now be described.

With the parts as illustrated in Fig. 1, 10 all the elevator gates are closed with the car at the landing designated 2, or the second floor we will say for example. Assuming now a power vehicle rides onto the approach landing *H* at the second floor. Now 15 by pressing the button *e*, the operation of the motor *K* is effected, which actuates the cam *J*, the latter in its operation by the motor, effecting the raising of both gates *G* simultaneously, the gates being maintained 20 in raised position by means of the cam *J* which in turn is maintained in actuated position by means of the dog 17. The circuits established by pressing the push button *e* may be traced as follows: from + 25 main, wire 33, relay winding 24, wire 34, button *e*, wire 35, thence to - line by way of contacts 29, shoe 30, wire 36. The relay winding 24 now being energized effects a closing of the contacts 25, which latter establish a self holding circuit for the relay winding, this circuit including the motor *K* and switch device 26, and being as follows: 30 wire 33, winding 24, contacts 25, wire 37, through motor *K*, wire 38, through switch device 26, wires 39 and 36 to - line. This self holding circuit including the motor *K* is maintained until the contact 27 rides off the segment 28, whereupon the self holding circuit is thus broken and likewise the motor 35 circuit.

It is to be pointed out here that by providing the contacts 29, controllable by the shoe 30 on the car, makes it possible to effect an operation of the motor *K*, to effect 40 the opening of the gates only by such button *e* as is located at the landing at which the elevator car is.

The gates *G* now being open, the vehicle rides on the elevator platform, and the operative thereof by a single thrust of the lower car push button *e* closes contacts 22 which establishes a circuit for the electro-magnet *L*, and also the contacts 23, which establishes a circuit for the down reversing 45 switch designated *R'*, which directs a source of current supply to the motor *M*, in a manner which causes the elevator car to descend. The circuit established by the contacts 22 may be traced as follows: from + wire to wire 40, to a wire 41 common to both car push buttons, contacts 22, wires 42 and 43, through winding of electromagnet *L*, wires 44, 36 and thence to - line. The electromagnet *L* now being energized effects the release of the dog 17 from the slot- 50

ted portion 18 of the cam, and the spring 21 thus acts to retract the cam to its inoperative position, and thus the gates *G* will close by their own weight.

The car operating circuit controlled by 70 the contacts 23 is well understood, the same being traced as follows: from + wire, wire 40 to junction 45, wire 46, through winding of the non-interference magnet to wire 47, through contacts 23 to wire 48, thence 75 through winding of the down reversing switch by way of the floor magnet and floor controller contacts, to - line. The non-interference magnet now operates in a well known manner to open its contacts, 80 thus opening the feed circuit wire 49 to the hatchway push buttons *b* and in this manner preventing interference therefrom. Upon the release of the car push button, the circuit for the winding of the reversing 85 switch and floor magnet is maintained through the floor magnet contacts and the floor controller contacts.

Now as the elevator car descends, the contact shoe 30 rides over the contacts 29' thus 90 effecting the operation of the motor *K* to actuate the cam *J*, in the same manner as by the push-buttons *e* heretofore described, the cam being maintained in actuated position by means of the dog 17. Now as the 95 car descends farther, the cam *J* coacts with the roller 16 thus actuating the traveler 10 and in this manner effecting the raising or opening of the hatchway gates at the first floor landing. The elevator car upon reaching the first floor landing is automatically stopped by means of the floor controller in a well understood manner, the cam *J* now maintaining the gates in raised position.

As the vehicle passes through the exit 105 gate and over the yieldable floor sections, the front and rear wheels thereof depressing both sections simultaneously, effects a closing simultaneously of both sets of contacts 4, which establishes a circuit for the 110 electro-magnet *L*, the latter operating the dog 17 to release the cam *J*, which is now moved to an inoperative position by the spring 21. In this manner it is seen, the gates will now close by their own weight, it 115 not being necessary for the operative of the vehicle to stop the same and return to close the said gates. The circuit for the electro-magnet *L* may now be traced as follows: from + wire to wire 40, to junction 40', 120 wires 50 and 51 to contact device *P* whose contacts are now closed, wire 52 to switch 5, wire 53, contacts 4 to wire 54, contacts 4 to wires 55 and 56, through winding of electromagnet *L* and thence to - line.

It is to be pointed out here that the circuit just traced includes the normally closed contact device 5, associated with the first floor entrance landing. The purpose of the switch 5, is to prevent the closing of the 130

- gates by the passage of a vehicle over the exit landing, in case there should be a vehicle at the opposite or entrance landing. Under this condition, the vehicle in waiting 5 at the entrance landing, depresses the yieldable floor section H, thus opening the contact device 5, and in this manner the circuit for the electromagnet L is broken at the said contact device, and the gates will remain 10 raised, thereby giving the operative of the vehicle at the entrance landing ample time to run his vehicle onto the elevator car. Thus when on the car, the vehicle operative presses the upper car push button, effecting 15 the closing of the gates and the operation of the elevator car in an ascending direction. The contacts 22 of both the car push buttons have similar functions, and the contacts 23 of the upper car button effect the 20 operation of the up reversing switch which switch closes, and directs the source of current supply to the motor M in a manner to cause the elevator car to ascend, the car being automatically stopped upon reaching 25 the second floor in a similar manner as heretofore described for the descending car.
- As the car ascends the contact shoe 30 rides over the contacts 29' effecting the actuation of the cam J, which, as the car approaches the upper floor landing, automatically effects the opening of the gates thereat, and the vehicle in passing off the car and over the exit landing, automatically effects the closing of the gates. The contact devices 5 at this landing operates in the same manner as heretofore mentioned, to prevent the gates closing in case there should be a vehicle in waiting at the entrance landing.
- It is to be pointed out here that only a 40 single yieldable floor section and contact device such as H and 4 respectively might be employed at each landing, but such a practice is considered dangerous since the gate might be caused to descend while the vehicle is part on and off the elevator car, by means of a person standing on the said section, whereas the use of two sections overcomes this danger to a great extent, it being further pointed out that the actuation of 45 both sections simultaneously is necessary in order to effect the closing of the gates. It is preferable to locate the floor section H nearest the gate, such a distance from the gate as to allow the truck to be free and 50 clear of the gate with the latter closed, the floor section farthest from the gate, or the one operable by the front wheels of the vehicle being spaced accordingly.
- It is to be further pointed out that each 55 of the contact devices P are in independent circuits, each one being connected in series with the contacts 4 of its associated landing, only, the purpose of these switches and the system of circuits being such that the operation of the electromagnet L to effect the

release of the cam J can be effected only from such exit landing at which the elevator car may be opposite and with the gates at that landing raised, these contact devices in other words being in the form of protective or non-interference devices. Without the provision of some such protective device there would be possibility of interference, if for any reason the contacts 4 should be actuated at an exit landing which 75 the elevator car has left, one particular instance being in case a vehicle should become stalled or for any other reason remain thereat.

The elevator car may be called to any 80 landing by means of the hatchway push buttons b which together with the push-buttons e need obviously be provided only at the landings designated "entrance". The system of control from the hatchway push 85 buttons is substantially the same as by means of the car push buttons, it being particularly pointed out that the gate contacts d are included in series with the common feed wire 49 leading to the hatchway buttons b, thus making it impossible to call the elevator car by means of these buttons until all the hatchway gates are closed.

Coming now to Fig. 2, it illustrates a modified mode of operation for certain of the gate controlling circuits, the most essential feature consisting in the provision of means whereby the opening of the hatchway gates may be automatically effected, simply by the passage of a vehicle onto an 100 entrance landing, instead of by means of the push buttons e as illustrated and described in connection with Fig. 1. In carrying out this idea, there is associated with each of the contact devices 5 at the entrance 105 landings, an additional set of contacts 57. These contacts are normally open, and are closed as indicated at the second floor landing by the depression of the floor sections H', thus establishing a circuit for the winding 24 of the relay O, which together with the contact device 26 controls a circuit for the motor K, which effects an opening of the gates by actuating the cam J. Assume now the elevator car is at the second landing and the gates thereat closed, which would be the result in case a vehicle passed off the elevator car and over the exit landing, before a vehicle arrived on the floor portion H' at the entrance landing. Assume further a vehicle now rides onto the second floor entrance landing thereby closing the contacts 57. The circuit controlled thereby may now be traced as follows: from + wire to wire 58, winding 24, wire 59, contacts 57, wire 60, contacts 29 and shoe 30 to wire 61 through a contact device P' controllable by the traveler 10, these contacts being closed with the gates closed, and thence by way of wire 62 to — line. The 110

operation of the relay O will now effect the opening of the gates in a manner just heretofore described.

- It will be noted that the contact device P' is included in the circuit just traced, one of the same being provided at each floor. The purpose of these contact devices, is to form a break in the circuit controlled by the contact 57 so as to eliminate or prevent wasteful or continued flow of current such as would result in case a vehicle should remain at the entrance landing for a considerable length of time, and with the elevator car at the corresponding landing. Thus it is seen that as soon as the gates start to rise or open, the contacts P' are opened, thus there can be no continued flow of current caused by the closure of the contacts 57. The contact devices P' may obviously be eliminated if so desired.

The arrangement of circuits and various parts for controlling the gate operation for the exit landing is the same as described in connection with Fig. 1, and thus needs no further description.

A system for operating and controlling elevator hatchway gates such as herein described, may be used to particularly good advantage in railway terminals, wherein power operated trucks are used extensively and in conjunction with elevators, for transferring baggage, etc., between different floors, a further use for the system being in conjunction with automobile hoists and hoists designed for raising and lowering street cars, etc.

Having thus described my invention, what I claim as new and desire to secure by Letters Patent of the United States is:—

- 40 1. In elevator apparatus, the combination with a car, a landing gate, and means controllable conjointly by the car and a vehicle for controlling the gate.
2. In elevator apparatus, the combination with a car, a landing gate, and means operable by a vehicle to control the gate only when the car is substantially at the landing.
3. In elevator apparatus, the combination with a car, a landing gate, and means comprising a weight controlled circuit-controlling device operable to control the gate only when the car is substantially at the landing.
4. In elevator apparatus, the combination with a car, a landing gate, a series of movable floor sections, contacts controlled by said sections, and an electric circuit including said contacts in series and controlling said gate.
- 60 5. In elevator apparatus, the combination with a car, a landing gate, a series of movable floor sections positioned a pre-determined distance from the gate, contacts controlled by said sections, and an electric cir-

cuit including said contacts in series controlling said gate. 65

6. In elevator apparatus, the combination with a car, a landing gate, and means at the landing controlling the gate, comprising a number of circuit controlling devices arranged in series. 70

7. In elevator apparatus, the combination with a car, a landing gate, and means at the landing controlling the gate, comprising a number of circuit controlling devices arranged in series, and a movable floor section adapted to operate each of said circuit controlling devices. 75

8. In elevator apparatus, the combination with a car, a landing gate, means on the car for maintaining the gate in open position, and weight-controlled mechanism located upon the landing controlling the first named means. 80

9. In elevator apparatus, the combination with a car, a landing gate, electrical means on the car to retain the gate in open position and weight controlled mechanism at the landing to control the electrical means. 85

10. In elevator apparatus, the combination with a car, a landing gate, electrically operated means on the car for retaining the gate in open position, and means comprising a yieldable floor section at the landing for controlling a circuit for the electrical means. 90

11. In elevator apparatus, the combination with a car, a landing gate, means on the car for retaining the gate in open position, electro-responsive means actuating the latter to effect a closing of the gate, and means comprising a circuit controlling device and a movable floor section at the landing for controlling a circuit for the electro-responsive means. 100

12. In elevator apparatus, the combination with a car, a landing gate, means for opening the gate, releasable means on the car for maintaining the gate in open position, and means comprising a movable floor section at the landing to control the releasable means. 110

13. In elevator apparatus, the combination with a car, a gravity actuated landing gate, means for opening the gate, a releasable member for maintaining the gate in open position, an electromagnetic means for releasing the same, and means comprising a number of switches arranged in series for controlling a circuit for the electromagnet. 115

14. In elevator apparatus, the combination with a car, a gravity actuated landing gate, means for opening the gate, a releasable member for maintaining the gate in open position, an electromagnet for releasing the same, and means operable from the car or at the landing for controlling a circuit for the electromagnet. 120

15. In elevator apparatus, the combination with a car, a gate, an electro-magnet, means releasable by said electromagnet for maintaining the gate in raised position, the 65
 5 means comprising a push button in the car, and weight controlled means at the landing for controlling a circuit for the electromagnet.
16. In elevator apparatus, the combination with a car, a landing gate, means for automatically opening the gate, electrically operated means for retaining the gate in open position, and a weight controlled device at the landing for controlling a circuit 70
 10 for the latter named means.
17. In elevator apparatus, the combination with a car, a landing gate, means for automatically opening the gate comprising a retractive cam on the car, electro-responsive 75
 20 means for actuating the cam, electrically operated means for retaining the gate in open position, a movable floor section, and means at the landing for independently controlling the electro-responsive means and the
 25 latter named means, comprising contact device operable by the movable floor section.
18. In elevator apparatus, the combination with a car, a landing gate, coacting means on the car and at the landing for 80
 30 opening the gate, electro-responsive apparatus for actuating the means on the car, and means at a landing for controlling a circuit for the said electro-responsive means.
19. In elevator apparatus, the combination with a car, a landing gate, coacting means on the car and at the landing for 85
 35 opening the gate, electro-responsive means for actuating the means on the car, means for retaining the gate in open position, an
 40 electro-responsive means for actuating the latter named means, and means for controlling a circuit for the said electro-responsive means comprising a weight controlled switch at the landing.
45. 20. In elevator apparatus, the combination with a car, a gravity closing landing gate, means comprising an electrically operated cam and coacting means for raising the gate, means for retaining the gate in raised 90
 50 position, and means at a landing controllable by a vehicle for independently controlling the opening and closing of the gate.
21. In elevator apparatus, the combination with a car, independent entrance and 95
 55 exit hatchway gates, coacting means on the car and at the landing for actuating the gates, and weight controlled means for controlling the opening and closing of the gates.
22. In elevator apparatus, the combination with a car, independent entrance and 100
 60 exit hatchway gates, coacting means on the car and at the landing operable to effect an opening and closing of the gates, and weight controlled means at the entrance and exit landing for independently controlling the 65
 gate operation.
23. In elevator apparatus, the combination with a car, independent entrance and exit gates at a landing, means for opening both gates simultaneously, and means controllable from the exit landing for retaining the gates in open position. 70
 75
24. In elevator apparatus, the combination with a car, independent entrance and exit gates at a landing, power mechanism for effecting opening of the gates, weight controlled means at the exit landing for controlling the closing of the gates, and means at the entrance landing for controlling the gate opening means. 80
 85
25. In elevator apparatus, the combination with a car, independent entrance and exit gates at a landing, means comprising power operated mechanism and a control system for automatically effecting the opening of the gates simultaneously, means controllable by a vehicle at the exit landing for controlling the closing of the gates, and means at the entrance landing correlated with the means at the exit landing to prevent closing of the gates by the vehicle controlled means at the exit landing. 90
 95
26. In elevator apparatus, the combination with a car, independent entrance and exit landing gates, power actuating mechanism for the gates, means controllable by a vehicle at the exit landing for controlling the closing of the gates, and means at the entrance landing correlated with the exit gate controlling means to prevent the closing of the gates, with a vehicle at the entrance and exit landing. 100
 105
27. In elevator apparatus, the combination with a car, independent entrance and exit landing gates operable by gravity, electrically operated mechanism for raising the gates simultaneously, means comprising an electromagnet for controlling the closing of the gates, and weight controlled switches at the entrance and exit landings, controlling the operation of the gate raising and closing means. 110
 115
28. In elevator apparatus, the combination with a car, independent entrance and exit landing gates operable by gravity, electrically operated mechanism for raising the gates simultaneously, means comprising an electromagnet for controlling the closing of the gates, and means on the car and at the exit landing controlling a circuit for the said electromagnet. 120
 125
29. In elevator apparatus, the combination with a car, independent entrance and exit landing gates, mechanism for automatically opening the gates simultaneously, means comprising an electromagnet for controlling the closing of the gates, and means comprising a push button in the car and a

weight controlled switch at the exit landing for controlling a circuit from the said electromagnet.

30. In elevator apparatus, the combination with a car, independent entrance and exit landing gates, means operable to effect an automatic opening of the gates simultaneously, means comprising an electromagnet controlling the closing of the gates, a movable floor section, and means comprising a push button in the car and correlated circuit controllers at the entrance and exit landings for controlling circuits for the said electromagnet, the said circuit controllers being operable by said movable floor section at the said landings.

31. In elevator apparatus, the combination with a car, entrance and exit landing gates operable by gravity, means for raising the gates simultaneously comprising an electrically operated cam, a releasable member for retaining the gates in raised position, an electromagnet for releasing the said member, yieldable floor sections at the entrance and exit landings, means at the exit landing controlling a circuit for the electromagnet comprising a number of circuit controllers arranged in series, each being operable by a yieldable floor section, a normally closed circuit controller operable by a yieldable floor section at the entrance landing, the said circuit controller being connected in series with the first named circuit controllers, and means at the entrance landing for controlling the gate raising means.

32. In elevator apparatus, the combination with a car, a number of landings, a gate at each landing, means for automatically opening the gates, releasable means for retaining the gates in open position, an electromagnet on the car for releasing the said means, means at each landing controlling a circuit for the said electromagnet, and means for preventing the establishment of a circuit for the said electromagnet from a landing other than that at which the car is.

33. In elevator apparatus, the combination with a car, a number of landings, a gate at each landing, means for automatically

opening the gates, releasable means for maintaining the gates in open position, electro-responsive means on the car for releasing the said means, and means at each landing operable only with the car thereat, for establishing a circuit for the said electromagnet.

34. In elevator apparatus, the combination with a car, a number of landings, a gate at each landing, means for opening the gates comprising a retractive cam on the car and automatically controlled electro-responsive means for actuating the same, and means at each floor for establishing a circuit for the said electroresponsive means.

35. In elevator apparatus, the combination with a car, a number of landings, a gate at each landing, means for opening the gates comprising a cam on the car and automatically controlled electro-responsive means for actuating the same, and an electric circuit for the said electro-responsive means controllable from each floor and only with the car thereat.

36. In elevator apparatus, the combination with a car, a hatchway gate, means for actuating the gate comprising a retractive cam and electro-responsive means for actuating the same, a releasable member co-acting with the cam to retain the same in actuated position, and an electromagnet operatively connected to the said releasable member.

37. In elevator apparatus, the combination with the car, a landing gate, power mechanism controlled automatically to open the gate, means to control the closing of the gate at will, and manual means at the landing to control the power mechanism to effect an opening of the gate subsequent to the said closure thereof.

In testimony whereof, I have signed my name to this specification in the presence of two subscribing witnesses.

FLOYD C. FURLOW.

Witnesses:

E. W. CALLAHAN,
C. E. BREITWEISER.
